COLLAPSIBLE TUBE SQUEEZER AND
BRUSH HOLDER

Nat Lipton, Long Beach, Calif.

Application October 22, 1947, Serial No. 781,473

3 Claims. (Cl. 222—93)

1

This invention relates to improvements in a collapsible tube squeezer and brush holder and more particularly to a one-piece integral construction for supporting a tube-squeezing means and toilet articles, as, for example, tooth brushes.

One object of this invention is to design and provide a one-piece integral member so constructed and formed from a blank of sheet material as to provide a means for attaching the member to a wall, a means for positioning and holding toilet articles, such as tooth brushes, while affording free circulation of air around said brushes, and a means for supporting tube-squeezing and holding apparatus.

Another object of this invention is to provide a one-piece integral member so constructed and formed as to position and hold a removable hollow cover which protects toilet articles from dust and dirt and which may be used for holding liquid.

A further object comprises the method of supporting the toothbrushes wherein they do not rest on the bristles but are supported by the shoulders of the toothbrush, the purpose of this being to properly aerate the bristles through the openings underneath in the supporting member which apertures are disposed in the same direction as the bristles when the latter are in their final resting position.

An additional object is to utilize an extending, arcuate flange which is part of and formed with the integral supporting member of the toothbrushing articles for the purpose of deflecting downwardly the extruded portion of the collapsible tube to the underside of the supporting member.

Another object is for the supporting member to have integrally formed upright flanges, at one or both terminal ends of the apertures receiving the toothbrush handles, for the purpose of retaining in position aforementioned toothbrush cover and also for the purpose of partially isolating the toothbrushes from each other.

This invention contemplates an article of manufacture of especial simple construction and design which is inexpensive, economical and efficiently manufactured. Generally speaking, this invention contemplates a one-piece integral member formed from a single, virtually rectangular blank of sheet material so formed as to provide a depending rear flange adapted to be secured to a supporting wall; a forwardly extending wall including a flat wall portion and a forwardly curved wall portion upwardly rising from the plane of the flat wall portion, spaced upstanding flanges integral with the flat wall portion and having forwardly directed extensions spaced from said curved wall portion, the forward extensions being provided with aligned means for supporting tube-dispensing rollers and the flat wall portion

2

being provided with means for positioning and holding selected toilet articles.

The drawings in this application constitute a preferred embodiment of the invention and, as such, are not intended to restrict the invention to the disclosed construction as long as the spirit of the invention is embraced therein.

One structural form of the invention is illustrated in the annexed drawings wherein Fig. 1 is a perspective view; Fig. 2 is a top plan view; Fig. 3 is a right side elevation; Fig. 4 is a rear view with a portion of the device broken away to disclose the manner in which a toothbrush handle is supported; Fig. 5 is a vertical cross-section taken on line 5—5 of Fig. 2 showing a portion of a toothpaste tube operatively supported by the device and further displays a portion of a toothbrush supported by the device; Fig. 6 is a fragmentary transverse cross-section taken on line 6—6 of Fig. 5; Fig. 7 is a plan view of a cut, metal blank from which the device is formed; and Fig. 8 is a vertical cross-section, similar to Fig. 5, of a modified form of the device.

The following detailed construction deals with a preferred form of the invention in Figs. 1 to 7 inclusive. The supporting member 1 can be punched and formed from one piece of metal or molded from plastic material, metal being the preferable substance. The member 1 includes a flat wall portion 2 provided with an integral rear depending flange 4 adapted to secure said member to a supporting wall. The flat wall portion 2 lies in a horizontal plane and a forwardly directed curved wall portion 11 is integrally formed with said flat wall portion and upwardly rises from the plane of the flat wall portion. The curved wall portion 11 includes a partial section of a cylinder of approximately 90°. Integrally formed and merging with opposite side edges of the flat wall portion 2 are a pair of spaced, upstanding, rigid flanges 3, each flange 3 being provided with a forwardly directed extension spaced from the side edges of the curved wall portion 11 and projecting beyond the forward edge of curved wall portion 11. The forward extensions are provided with spaced perforations or apertures 6 transversely aligned for carrying in spaced relation rods 5. Rods 5 can be either solid or hollow and are journaled in apertures 6, being supported and rotated therein. The terminal ends of rods 5 can be the same diameter as the remainder of the rods since lateral movement to dislodge the rods is obviated by the rubber rollers 7. If desirable, the terminal ends of rods 5 can be flattened or rivet headed (if the rods are solid) or flared (if the rods are hollow). Rubber rollers 7 are cut from soft rubber tubing through which rods 5 are thereafter pressed. Apertures 6 are spaced in fixed relation so that the rubber rollers 7 are in light contact with each other. Located at the

extremities of rubber rollers 7 are metal washers 8 which act as anti-friction bearings against the inner walls of flanges 3. The use of washers 8 is optional but desirable since the rubber of rollers 7, when in direct contact with the inner walls of flanges 3, induce friction and consequent difficulty in the manual rotation of knob 9 ensues.

When the sealed end of a collapsible tooth-paste tube 10 is inserted between rollers 7, and knob 9 is rotated in a clockwise direction, the tube 10 is propelled upwards and the contents of the tube are expelled through the open end of the tube. The inner surface of the curved wall portion 11 may conform to the peripheral surface of one or both rollers 7, and can be of any predetermined length, as desired, extending to any point along the dotted lines in Fig. 5, preferably to a point past the roller adjacent to flange 11. The clearance between the flange 11 and adjacent roller 7 should permit only for the thickness of the compressed portion of tube 10, the reason therefor being that the tube 10 has a tendency to force its way straight upwardly. Therefore, tube 10 will not readily be deflected downwardly unless it is kept in contact with the roller 7 adjacent flange 11, and urged toward its downward course by the friction of said rubber roller.

The flat wall portion 2 is adapted to carry toilet articles, such as tooth brushes, as illustrated, and is provided with longitudinally disposed elongated spaced apertures 12. The width of rectangular-like apertures 12 is less than the width of the uppermost portion of the toothbrush handle 13 above the neck of said toothbrush; the width of apertures 12 is wider than the width of the neck of the toothbrush handle 13; the length of apertures 12 is slightly longer than the widest part of the toothbrush handle 13. Toothbrush handle 13 is inserted with the toothbrush bristles 14 parallel to the rollers 7 and when the neck of said toothbrush is on a plane with base 2 it is given a quarter turn forward so that the bristles 14 are at right angles to rollers 7. Toothbrush 13 will therefore be supported by the shoulders thereof on base 2 of supporting member 1.

The excess metal from which apertures 12 are formed as by a punching operation is not cut free from the flat wall portion 2 but is preferably bent into a plane perpendicular to the plane of the flat wall portion 2, thus providing tooth brush positioning and holding elements or ears 15. Upright ears 15 at the terminal points of apertures 12 preclude, to a certain extent, the forward and backward motion of toothbrushes 13 and also serve to partially isolate the toothbrushes from each other. A toothbrush cover 16 is furnished which can be metal or plastic, preferably plastic, and is retained in position by its forward segment resting outside the foremost ears 15, its rear segment resting outside the furthermost ears 15, and its side segments positioned inside of the upright members 3. The supporting member 1 is secured to a wall through apertures 17 located on flange 4.

In the modification displayed in Fig. 8, a third coating roller 18 is placed in slight contact with the rearward roller 7. The clockwise rotation of knob 9 propels upwardly the sealed end of a collapsible tube inserted between the two foremost rollers 7 and simultaneously deflects downwardly the extruded portion of said collapsible tube between the two rearmost rollers 7 and 18.

The collar of collapsible tubes being constructed of heavier metal does not readily lend itself to collapsible methods. The construction of the roller elements being semi-circular in effect con-

forms to some degree to the cup-like shape of the tube collar. When the point is reached where the collar prevents the further normal rotation of the roller elements, it is possible to expend practically all the contents of the tube by applying both thumbs against the collar and compressing the collar against the roller elements.

It is not intended to claim as invention the process itself of compressing a collapsible tube by propelling said tube between two rollers which rotate on their respective axes since this feature has been disclosed in prior invention. However, the elements that distinctly comprise novelty or improvement are considered invention and in this respect, I claim:

1. An article of manufacture comprising a one-piece integral member including a depending flange at one end adapted to be secured to a supporting wall; a forwardly extending wall including a flat wall portion lying in a horizontal plane integral with the top edge of said depending flange and a forwardly curved wall portion upwardly rising from the plane of the flat wall portion for downwardly guiding an emptied portion of a tube dispenser; said flat wall portion having spaced longitudinally elongated perforations therein for carrying tooth brushes; and spaced, rigid, upstanding flanges for reinforcing said forwardly extending wall for rigidity, each integral with a side edge of said flat wall portion and extending entirely along the length of said side edge and each having a forward extension spaced from said curved wall portion; said forward extensions being provided with spaced aligned ports for supporting tube dispensing roller means.
2. An article of manufacture as defined in claim 1 wherein at least one end of each of said perforations is provided with an upstanding element for positioning and holding a tooth brush with the bristles disposed above a portion of the perforation.
3. In an article of the character described, the combination of: a one-piece integral member of sheet material including a flange at one end adapted to be secured to a supporting wall; a forwardly extending wall including a flat wall portion lying in a horizontal plane integral with said flange and an upwardly rising, forwardly directed, curved wall portion integral with said flat wall portion; said flat wall portion having means integral therewith for positioning and holding toilet articles; and spaced upstanding flanges, each integral with a side edge of said flat wall portion, extending for the entire length of the said side edge, and having an extension spaced from said curved wall portion and extending forwardly therebeyond; said extensions being provided with spaced transversely aligned ports for journalably supporting tube-dispensing roller means.
